Application October 21, 1933, Serial No. 694,650
In Great Britain November 4, 1932

9 Claims. (Cl. 163—37)

This invention relates to displacement pumps of the type comprising a pair of co-acting displacers, such as plungers, actuated by separate crank-shafts, and working in a common chamber, 5 or a plurality of pairs of co-acting displacers, each pair working in a common chamber the volumetric discharge from which chamber or each of which chambers is varied by varying the phase relation of the crankshafts.

10 When the crankshafts are in phase, the volumetric displacement is the maximum; when the crankshafts are in opposite phase relation, the volumetric displacement is the minimum.

15 It is known to drive the two crankshafts by means of two synchronous motors and to vary the relative timing of the two crankshafts by partially rotating the stator of one motor so as to alter the position of the poles of said stator 20 relatively to the poles of the stator of the other motor, and thereby to alter the relative timing of the two crankshafts.

25 In the pump according to the present invention the crankshafts are normally driven at equal speeds by motors having fixed stators, associated with means controlled by the delivery pressure 30 of the pump and adapted momentarily to bring about differential speeding of the rotors of said motors whereby to change the relative timing of the crankshafts driven by said motors.

35 In the accompanying drawings which illustrate the invention Fig. 1 shows diagrammatically a variable delivery displacement pump driven by two induction motors coupled to D. C. machines, the plungers being shown in phase corresponding to maximum delivery. Fig. 2 shows diagrammatically the same pump as in Fig. 1 but with the plungers in opposite phase corresponding to maximum delivery. Fig. 3 shows a modified arrangement of the hunting controller. Fig. 4 shows a further modified arrangement of the hunting controller. Fig. 5 shows diagrammatically an arrangement incorporating a slip-ring motor having a variable rotor resistance, the 40 plungers being shown in phase. Fig. 6 is a view similar to Fig. 5 but with the plungers shown out of phase. Fig. 7 is a fragmentary view showing a further modification incorporating two slip-ring induction motors with variable rotor resistances.

45 Referring to Figs. 1 and 2 of the drawings, 1 and 1a denote two co-acting plungers driven by separate crank shafts 5 and 5a, respectively, and adapted to operate in a common chamber 2 provided with a suction valve 3 and with a discharge 50 valve 4. As shown in Fig. 1, the crankshafts 5

and 5a are in phase, so that the volumetric displacement of the plungers 1 and 1a is the maximum. The crankshafts 5 and 5a are driven normally at equal speeds through gearing 7 and 7a by induction motors 6 and 6a which are preferably of the squirrel-cage type. Directly coupled to the motors 6 and 6a are two D. C. machines 8 and 8a the armature circuits of which are coupled in opposition, so that with equal fields the same voltage is generated in each and no current flows. The delivery pressure in the pump discharge pipe 9 acts on one end of a piston 10 in opposition to a spring 11 acting on the other end of said piston 10. A spindle 12 attached to the piston 10 is operatively connected to the sliding contact 13 of a potentiometer 14.

55 The crankshafts 5 and 5a drive bevel wheels 15 and 15a, shafting, and bevel wheels 16 and 16a of a differential gear. Meshing with the bevel wheels 16 and 16a are two intermediate bevel 60 wheels 17 and 18 journalled in a casing 19 rotatable about the common axis of the bevel wheels 16 and 16a and presenting a cam 20 cooperating with a follower on a spindle 21 connected to the potentiometer 14. The potentiometer resistor is 65 coupled in series with the fields 22 and 22a of the D. C. machines 8 and 8a, the brushes of which machines are coupled to form a circuit 23 electrically connected to the contact 13 of the potentiometer 14.

70 With the contact 13 in mid position with respect to the resistor the voltage generated by the machine 8 is equal to the voltage generated by the machine 8a and no current flows in the circuit 23. If, however, the contact 13 is moved to unbalance 75 the resistance, for example to insert additional resistance in the field 22, and to cut out resistance from the field 22a, the D. C. machine 8a becomes a generator while the D. C. machine 8 becomes a motor, thus transferring power from the shaft of 80 the induction motor 6a to the shaft of the induction motor 6. The effect is to increase the speed of the armature of the induction motor 6 and to 85 reduce the speed of the armature of the induction motor 6a, so that the crankshafts 5 and 5a are 90 differentially speeded to bring about variation in the relative timing of said crankshafts and so vary 95 the volumetric displacement of the plungers 1 and 1a.

100 When the crankshafts 5 and 5a are differentially speeded, the bevel wheel drive 15 and 15a causes the casing 19 partially to rotate the cam 20 and thereby displace the potentiometer 14 until the contact 13 is again at the mid-point of the resistor, when the resistances in the fields 22 and 110

22a will again be equal. No current will then flow in the circuit 23, the D. C. machines 8 and 8a will generate equal voltages, and the armatures of the motors 6 and 6a will again rotate at equal speeds, the crankshafts 5 and 5a being now out of phase.

Fig. 2 shows the plungers in the opposite phase position corresponding to minimum pump delivery. It will be understood that, by varying the phase relation of the two crankshafts 5 and 5a between the position shown in Fig. 1 and the position shown in Fig. 2, any pump delivery between maximum capacity and minimum capacity can be obtained. The pressure in the pump delivery pipe 9 controls the position of the piston 10 which is the first part of the hunting controller, movement of the piston 10 being communicated to the potentiometer contact 13 which causes the requisite differential speeding of the armatures of the motors 6 and 6a to produce the required change in the phase relation of the crankshafts 5 and 5a. The change in the phase relation of the crankshafts 5 and 5a causes the second part of the hunting controller, comprising the parts 15 to 21, to displace the potentiometer 14 in the direction to restore the resistor to equilibrium position so that the delivery pressure in the pipe 9 and the pump output are in the desired relation. For any given delivery pressure there is a corresponding phase relation of the crankshafts 5 and 5a and therefore a corresponding pump output. As shown in Fig. 1, when the crankshafts 5 and 5a are in phase, the cam 20 is in its maximum throw position and the piston 10 is in its uppermost or minimum delivery pressure position. Conversely, and as shown in Fig. 2, when the crankshafts 5 and 5a are in opposite phase, the cam 20 is in its minimum throw position and the piston 10 is in lowermost or maximum delivery pressure position. Thus, in the construction according to Figs. 1 and 2, the delivery pressure will fall continuously from minimum pump output corresponding to the opposite phase position shown in Fig. 2 to maximum pump output corresponding to the in-phase position shown in Fig. 1, so that the pressure capacity characteristic of the pump will fall continuously from no load to full load.

In the modification shown in Fig. 3 the cam 20 of the hunting controller is so arranged that the delivery pressure of the pump will rise continuously from no load to full load and the pressure capacity characteristic of the pump will closely approximate to the resistance capacity characteristic of the delivery system, the power required to drive the pump being thereby reduced to the minimum for all capacities.

In this arrangement the spindle 21 acts on one end of a floating lever 13' carrying the contact 13, the other end of said lever being operated by the piston 10 through the spindle 12. The lever 13' holds the contact 13 at mid position of the potentiometer when a given pump output corresponds to the predetermined delivery pressure for that output.

With a fall in pressure the piston 10 and spindle 12 rise, and raise the contact 13 relatively to the resistance 14. In consequence, the output of the pump will be increased until the spindle 21 is lowered and lowers the contact 13 to mid position. Conversely, with rise in pressure the piston 10 and spindle 12 will be lowered, the contact 13 will be lowered relatively to the resistance 14, and the output of the pump decreased.

Fig. 4 shows an alternative arrangement of the hunting controller to obtain a rising pressure ca-

80 pacity characteristic. The position of the spindle 21 actuated by the cam 20 determines the position of the spring base 21a in accordance with the relative timing of the crankshafts. For any given output of the pump the delivery pressure causes a corresponding compression of the spring 11. The contact 13 being normally in mid position on the potentiometer 14, with a fall in delivery pressure, due to the output being smaller than the demand, the spring 11 will be partially unstressed and contact 13 will rise. At the same time as the pump output is increased due to the rise of the contact 13, the base 21a is displaced in the direction to restore the contact 13 to mid position whereupon the pump continues to run at increased output. Oppositely directed movements of the contact 13 and base 21a are brought about by an increase in delivery pressure due to the output being greater than the demand.

90 In the construction according to Fig. 3 or Fig. 4 the cam 20 is in its maximum throw position as shown when the crankshafts are in phase giving maximum output, when the piston 10 is fully depressed under maximum delivery pressure, and when the contact 13 is positioned at the mid point 100 of the potentiometer 14. Conversely, when the cam 20 is in minimum throw position corresponding to minimum output, with the contact 13 at mid position, the piston 10 will be located in fully raised position corresponding to minimum delivery pressure. Manifestly, either arrangement is such as to produce a rising pressure capacity characteristic in contradistinction to the arrangement according to Figs. 1 and 2 as evidenced by the relative positions of the cam 20, 110 contact 13 and piston 10 as shown in these figures.

115 While there has been described a differential gear driven by the crankshafts as constituting the operating mechanism of the second part of the hunting controller, it will be understood that the second part of the hunting controller may be actuated by any portion of the electrical or driving mechanism having a definite position for any given relative timing of the crankshafts, i. e., operating in synchronism with the change of relative timing of the crankshafts.

120 The second part of the hunting controller may comprise electrical devices. For example, the armature speeds of the driving motors are equal when there is no flow of current through the circuit 23, whereas, when the armatures are differentially speeded, there is a flow of current through the circuit 23 and this flow may be utilized to operate a motor, solenoid, or other device for the purpose of restoring the potentiometer to 130 equilibrium position after a movement of the potentiometer effected by the first part of the hunting controller.

125 Referring to Figs. 5 and 6, the crankshaft 5a is driven by a squirrel-cage motor 26 having a relatively high resistance rotor running at a substantially constant speed. The crankshaft 5 is driven by a slip-ring induction motor 25 the rotor circuit of which is provided with a variable resistor 27, so that by variation of the resistance in 140 the rotor circuit, due to movement of the contacts 28, caused by a change in delivery pressure in the pipe 9 acting on the piston 10, the speed of the rotor of the motor 25 is increased or reduced relatively to the speed of the rotor of the motor 26 for the period of time necessary to change the relative timing of the crankshafts 5 and 5a to bring about the requisite change in pump output. Any movement of the piston 10, which is 145 the first part of the hunting controller, varies 150

the resistance and causes a variation in the relative timing of the two crankshafts by differentially speeding the rotors of the two motors 25 and 26, while the changing of the relative timing of the two crankshafts causes the second part of the hunting controller, comprising the parts 15 to 21, to restore the resistor to the position at which the speed of the armature of the slip-ring motor 25 is equal to the speed of the rotor of the squirrel-cage motor 26 with the pump output modified as required by the delivery pressure.

As shown in Fig. 7 both motors 25 and 26a are of the slip-ring induction type with variable rotor resistances 27, 27a arranged to increase the speed of the rotor of the motor 26a when the speed of the rotor of the motor 25 is being reduced and to decrease the speed of the rotor of the motor 26a when the speed of the rotor of the motor 25 is being increased.

20 It should be understood that the structure shown in Fig. 7 will be equipped with a differential follow-up mechanism such as is shown in the other figures of the drawings.

What we claim is:—

25 1. In a displacement pump, in combination, a displacement chamber, at least one pair of displacers working in said chamber, separate shafts for driving said displacers, motors having fixed stators and rotors normally rotating at equal speeds for driving said shafts, and means controlled by the pressure of the discharged fluid and adapted momentarily to cause differential speeding of said rotors to vary the relative timing of said shafts.

35 2. In a displacement pump, in combination, a displacement chamber, at least one pair of displacers working in said chamber, separate shafts for driving said displacers, a substantially constant speed motor driving one of said shafts, a motor having a fixed stator and a variable speed rotor adapted normally to drive the other of said shafts at the same speed as the first mentioned shaft, and means controlled by the pressure of the discharged fluid for momentarily varying the speed of said rotor to change the relative timing of said shafts.

45 3. In a displacement pump, in combination, a displacement chamber, at least one pair of displacers working in said chamber, separate shafts for driving said displacers, motors having rotors normally rotating at equal speeds for driving said shafts, and means for momentarily causing differential speeding of said rotors to vary the relative timing of said shafts, said means comprising a part controlled by the pressure of the discharged fluid, and a part controlled in synchronism with the variation of the relative timing of said shafts.

50 4. In a displacement pump, in combination, a displacement chamber, at least one pair of displacers working in said chamber, separate shafts driving said displacers, motors having armatures rotating normally at equal speeds for driving said shafts, and means for initiating and then discontinuing differential speeding of said armatures to vary the relative timing of said shafts, said means giving a delivery pressure falling from a maximum at zero discharge to a minimum at maximum discharge, and comprising a part controlled by the pressure of the discharged fluid and a part controlled in synchronism with the variation of the relative timing of said shafts.

55 5. In a displacement pump, in combination, a displacement chamber, at least one pair of dis-

placers working in said chamber, separate shafts driving said displacers, motors having armatures normally rotating at equal speeds for driving said shafts, and means for initiating and then discontinuing differential speeding of said armatures to vary the relative timing of said shafts, said means giving a delivery pressure rising from a minimum at zero discharge to a maximum at maximum discharge, and comprising a part controlled by the pressure of the discharged fluid and a part controlled in synchronism with the variation of the relative timing of said shafts.

6. In a displacement pump, in combination, a displacement chamber, at least one pair of displacers working in said chamber, separate shafts driven by said displacers, motors for rotating said shafts normally at equal speeds, means controlled by the pressure of the discharged fluid for initiating differential speeding of said motors to vary the relative timing of said shafts, a differential gear including a member responsive to variation in the relative timing of said shafts, and means cooperative with said member for restoring the relative speeds of said motors.

7. In a displacement pump, in combination, a displacement chamber, at least one pair of displacers working in said chamber, separate shafts driving said displacers, motors for rotating said shafts normally at equal speeds, D. C. machines coupled to said motors and having armature circuits connected in opposition, a potentiometer controlling the field circuits of said machines, and means comprising a device responsive to the pressure of the discharged fluid and acting on said potentiometer to initiate differential speeding of said motors to vary the relative timing of said shafts, and mechanism responsive to variation of the relative timing of said shafts and acting on said potentiometer in opposition to said device to restore equality of speeds of said motors.

8. In a displacement pump, in combination, a displacement chamber, at least one pair of displacers working in said chamber, separate shafts driving said displacers, a substantially constant speed motor driving one of said shafts, a slip-ring induction motor with variable rotor resistance driving the other of said shafts normally at the same speed as the first shaft, means comprising a device responsive to the pressure of the discharged fluid for varying the speed of said induction motor to vary the relative timing of said shafts, and mechanism responsive to variation of the relative timing of said shafts and operating in opposition to said device to vary said rotor resistance to discontinue the differential speeding of said motors.

9. In a displacement pump, in combination, a displacement chamber, at least one pair of displacers working in said chamber, separate shafts driving said displacers, slip-ring induction motors with variable rotor resistances driving said shafts normally at equal speeds, and means comprising a device responsive to the pressure of the discharged fluid for varying said rotor resistances whereby to initiate differential speeding of said motors to vary the relative timing of said shafts, and mechanism controlled in synchronism with the variation of the relative timing of said shafts and operating in opposition to said device.

HAROLD HILLIER.
